CLAIM

The ornamental design for an athletic training apparatus, as shown and described.

DESCRIPTION

FIG. 1 is a top left and front perspective view of the athletic training apparatus showing my new design.

FIG. 2 is a front view thereof.

FIG. 3 is a rear view thereof.

FIG. 4 is a right side view thereof; and,

FIG. 5 is a left side view thereof.

The broken lines are included for the purpose of illustrating features of the athletic training apparatus that form no part of the claimed design.

The variations in the position of some portions of the design are due to their flexible nature.
